(57) **CLAIM**

The ornamental designs for a laser projection tool, as shown and described.

DESCRIPTION

FIG. 1 is a perspective view of one embodiment of a laser projection tool with its lid down;

FIG. 2 is a right side view of the laser projection tool shown in FIG. 1 with the left side view being substantially a mirror image thereof;

FIG. 3 is a top view of the laser projection tool shown in FIG. 1;

FIG. 4 is a bottom view of the laser projection tool shown in FIG. 1;

FIG. 5 is a front side view of the laser projection tool shown in FIG. 1;

FIG. 6 is a rear side view of the laser projection tool shown in FIG. 1;

FIG. 7 is a perspective view of the laser projection tool shown in FIG. 1 with its lid up;

FIG. 8 is a right side view of the laser projection tool shown in FIG. 7 with the left side view being substantially a mirror image thereof;

FIG. 9 is a top view of the laser projection tool shown in FIG. 7;

FIG. 10 is a bottom view of the laser projection tool shown in FIG. 7;

FIG. 11 is a front side view of the laser projection tool shown in FIG. 7;

FIG. 12 is a rear side view of the laser projection tool shown in FIG. 7;

FIG. 13 is a perspective view of another embodiment of a laser projection tool with its lid up;

FIG. 14 is a right side view of the laser projection tool shown in FIG. 13 with the left side view being substantially a mirror image thereof;

FIG. 15 is a top view of the laser projection tool shown in FIG. 13;

FIG. 16 is a bottom view of the laser projection tool shown in FIG. 13;

FIG. 17 is a front side view of the laser projection tool shown in FIG. 13; and,

FIG. 18 is a rear side view of the laser projection tool shown in FIG. 13.

The broken lines showing the environment of the laser projection tool are for environmental purposes only and do not form any part of the claimed designs.
